UNITED STATES PATENT OFFICE.

VERNON TEEL, OF TROUSDALE, OKLAHOMA.

CUSHION FOR CHAIR ROCKERS.

Application filed May 17, 1926. Serial No. 109,708.

This invention relates generally to chairs of the rocker type, and has more particular reference to a cushion for the rockers thereof.

5 The primary object of the invention is to provide a cushion for chair rockers that is so constructed as to permit of the ready application or removal of the same with respect to the rockers, and that when so attached 10 are not liable to become accidentally displaced therefrom.

The invention further aims to provide novel and efficient means to permit the permanent attachment of the cushions upon the 15 rockers, and as to readily permit the detachment of the same with respect thereto.

Other objects of the invention will become apparent as the nature thereof is better understood, the cushions comprising 20 the novel form, combination and arrangement of parts hereinafter more fully described, shown in the accompanying drawing and claimed.

In the drawing wherein like reference 25 characters indicate corresponding parts throughout the several views:

Figure 1 is a fragmentary side elevation of a conventional rocking chair, the rocker thereof disclosed being equipped with a 30 cushion constructed in accordance with the present invention.

Figure 2 is a fragmentary perspective of one end of a chair rocker upon which has been arranged my improved cushion, and 35 prior to the attachment of the same thereto.

Figure 3 is an end elevation of the cushion as partially attached to the rocker.

Figure 4 is a detail longitudinal section of one end of the rocker and cushion, and 40

Figure 5 is a view similar to Figure 3, disclosing the cushion as fully attached to the rocker.

In the drawing, the numeral 5 designates 45 generally a conventional form of rocking chair, and 6 one of the rockers thereof. My improved cushion constitutes the provision of a length of rubber or other suitable compressible material that is of a length equivalent to the length of the particular rocker 50 to which it is to be associated, and is of relatively U-shape in cross section as disclosed in Figure 2, said cushion being designated by the reference character 7. At this point 55 it may be well to state that the side walls of the cushion are in such spaced relation as to snugly engage the sides of the rocker

6 as to prevent the vertical displacement of the same therefrom.

The upper edges of the side walls of the cushion 7 are beaded as at 8-8 and running longitudinally therethrough are lengths of flexible wire 9-9 that project considerably outwardly of the cushion at the opposite ends thereof as clearly disclosed in Figure 2. Also passing longitudinally through the bottom wall of the cushion at opposite ends thereof are other lengths of flexible wire 10-10 that also extend beyond the cushion at opposite ends thereof.

In actual practice the cushion carrying the 70 wires 9-9 and 10-10 is arranged upon the rocker 6 in the manner as disclosed in Figure 2. After the cushion has been so arranged, there is inserted at the opposite ends of the rocker and between the rocker and the 75 bottom wall of the cushion a predetermined length of leather or other suitable heavy fabric 11 that extends outwardly of the ends of the rocker and the cushion as disclosed.

The extreme outer edge of this length of 80 rubber or leather is turned over as at 12 and is so stitched to the body as to provide a pair of pockets 13-13 at the opposite ends thereof. The wires 10-10 are engaged at 85 their ends within the pockets 13-13 after which the leather or fabric is bent upwardly into the position shown in Figure 3. The ends of the wires 9-9 are then bent across the ends of the rocker and joined by twisting as shown in Figure 3. The portions of the 90 wires 10-10 above the wires 9-9 as well as the leather or fabric above the wires 9-9 are then bent downwardly as per Figures 4 and 5 to cover the wires 9-9 as well as the twisted ends thereof to prevent the catching of the garments or the like in said 95 twisted ends of these connected wires.

Having thus described the invention, what I claim as new and desire to secure by Letters Patent is:-

1. In a chair rocker cushion, a substantially U-shaped cushioning member of substantially the same length as the rocker and in which the rocker is adapted to fit, wires 100 extending longitudinally through the respective sides of the U-shaped cushioning member, additional wires extending longitudinally through the base portion of the cushioning member, the ends of all the wires 105 projecting beyond the respective ends of the rocker and the cushioning member, the free 110 ends of the side wires extending transversely

across the respective ends of the rocker and being secured together, the free ends of the wires which extend longitudinally through the base portion of the U-shaped cushioning member being disposed upwardly adjacent the respective ends of the rocker, and thence bent downwardly over the interconnected transversely extending ends of the aforementioned side wires.

10 2. In a chair rocker cushion, a substantially U-shaped cushioning member of substantially the same length as the rocker and in which the rocker is adapted to fit, wires extending longitudinally through the respective sides of the U-shaped cushioning member, additional wires extending longitudinally through the base portion of the cushioning member, the ends of all the wires projecting beyond the respective ends of the 15 rocker and the cushioning member, the free ends of the side wires extending transversely across the respective ends of the rocker and being secured together, the free ends of the wires which extend longitudinally 20 through the base portion of the U-shaped cushioning member being disposed upwardly adjacent the respective ends of the rocker, and thence bent downwardly over the interconnected transversely extending ends of the 25 aforementioned side wires, and a covering for the end portions of the wires.

3. In a chair rocker cushion, a substantially U-shaped member of a length equivalent to the length of the rocker and in which

the rocker is adapted to fit, a bead formed 25 on each upper edge of the U-shaped member, a wire extending longitudinally through each bead, additional wires extending longitudinally through the base portion of the cushioning member, the ends of all said 30 wires projecting beyond the ends of the cushioning member and the rocker, a strip of flexible material insertible between the bottom of the cushioning member and each 35 end of the rocker, pockets formed in the outer end portion of the strip for receiving the free ends of the wire which extend longitudinally through the base portion of the cushioning member at each end 40 of the rocker, the outer end portions of the strips which project beyond the respective 45 ends of the rocker and the end portions of the wires disposed in the aforementioned 50 pockets being disposed upwardly adjacent the respective ends of the rocker, the ends 55 of the wires which extend longitudinally through the beads being disposed transversely across the upwardly bent ends of the wires attached to the flexible member, the free 60 ends of the transversely disposed wires being twisted together, the outer free end portions of the strips and the ends of the wires within said pockets being bent 65 downwardly over transversely extending interconnected wires.

In testimony whereof I affix my signature.

VERNON TEEL.
